United States Patent Office.

DANIEL DEAN, OF BRIGHTON, MICHIGAN.

Letters Patent No. 79,451 dated June 30, 1868.

IMPROVEMENT IN CULTIVATOR-TOOTH.

The Schedule referred to in these Letters Patent and making part of the same.

TO ALL WHOM IT MAY CONCERN:

Be it known that I, DANIEL DEAN, of Brighton, in the county of Livingston, and State of Michigan, have invented a new and useful Improvement in Reversible Cultivator-Teeth; and I do hereby declare the following to be a full and correct description of the same, sufficient to enable others skilled in the art to which my invention appertains to fully understand and use the same, reference being had to the accompanying drawings, which make part of this invention, and in which—

Figure 1 is a perspective view of my improved reversible cultivator-tooth.

Figure 2 is a cross-section of the same in line x x , fig. 1.

Figure 3 is a perspective view of the same when in operation on very young corn, and

Figure 4 a like view when in operation on older corn.

Like letters of reference indicate like parts in the several drawings and figures.

The object of this invention is to construct a cultivator-tooth, that by merely turning on its standard, it may be used for either throwing up small hills on young corn-plants or making the hills larger for grown ones.

In order to accomplish this, I construct a double-pointed curved tooth, A, of steel or other suitable material, with two sides, B C, which form an obtuse angle in relation towards each other, the side B being considerably narrower than side C. D is the bolt-hole in the centre of the length of the tooth and in the angle where sides B and C meet, through which bolt-hole passes the bolt by means of which the tooth is secured to its standard, the bolt passing through the latter, and being secured by a nut or in any other suitable way, always permitting it to be loosened to allow the tooth to be turned. E F represent the two points of the tooth.

In fig. 3 the tooth is shown attached to the standard in position to throw up small hills on young plants, the point F being in the ground, and side B operating against the plants. By merely loosening the screw on the standard, the tooth may be reversed so as to have a position as shown in fig. 4, the point E now being in the ground and the side C operating in throwing up large hills around the older plants.

By means of employing this tooth the same cultivator-frame will do for early and later cultivating of corn, without the necessity of changing one set of teeth for another.

Having thus described my invention, what I claim as new, and desire to secure by Letters Patent, is—

The reversible cultivator-tooth A, when constructed substantially as shown and for the purposes described.

DANIEL DEAN.
